[57] ABSTRACT

The pipe jack includes a square tubular body, and a movable carriage and a hydraulic ram mounted within the body. A cylindrical sleeve for receiving a length of pipe or rod is disposed above the body and is removably mounted on the carriage. A gripper, including a two-piece arcuate clamp and a hydraulic ram, grips the pipe or rod adjacent the sleeve. When the carriage is moved, the sleeve engages the gripper to move the pipe or rod.

5 Claims, 5 Drawing Figures

PIPE JACK

BACKGROUND

The invention pertains generally to pushing and pulling implements and more particularly to pipe or rod jacks.

One use of pipe jacks is to install water lines in buildings. A pit is dug at street side, and a pipe having a pointed end is forced from the basement to the pit. The water line is then drawn through the pipe, and the pipe retracted. Various apparatus have been suggested for this operation. Manually operated apparatus require too much physical labor. Other apparatus appears too complex.

SUMMARY

The present invention pertains to an improved pipe jack. The term "pipe jack" being meant to include the operation of pushing and/or pulling a pipe or rod.

It is a general object of this invention to provide an improved pipe jack.

Another object is to provide an improved pipe jack for jacking a pipe and the like through the earth as in installing a water line into the basement of a building.

Yet another object is to provide a pipe jack which is capable of use in cramped spaces and convenient for transportation to and from the job and into and out of the basement of a building.

Another object of the invention is to provide a pipe jack which is easily manipulated or controlled for actuating a piercing rod step by step in either direction.

A further object of the invention is to provide a pipe jack which is not only capable of providing a hole through the ground by forward piercing action but also for return pulling therethrough for installation therein the water pipe or the like.

A still further object is to provide a pipe jack that is of simplified construction, economical to manufacture, and simple and efficient to use.

These, and other objects and advantages of the present invention, will become apparent as the same becomes better understood from the following detailed description when taken in conjunction with the accompanying drawings.

DRAWINGS

FIG. 1 is a top view of a pipe jack constructed in accordance with the present invention;

FIG. 2 is a view as seen from line 2—2 of FIG. 1 and on a larger scale than FIG. 1;

FIG. 3 is a view taken along line 3—3 of FIG. 1 and on a still larger scale which is half size;

FIG. 4 is a front elevation of the pipe jack of FIG. 1 with the carriage in extended position; and

FIG. 5 is a view, partly sectional and partly elevational, taken generally along line 5—5 of FIG. 4, but with the carriage retracted.

DESCRIPTION

Reference is now made more particularly to the drawings which illustrate the best presently known mode of carrying out the invention and wherein similar reference characters indicate the same parts throughout the several views.

The pipe jack has a tubular body 10 provided with a number of outwardly extending legs 12 having openings 13 through which pins or anchors can be inserted

to secure the pipe jack in position as, for example, into holes drilled into a basement floor. Alternatively, the openings 13 in the rear legs 12 (at the left of FIGS. 1, 4 and 5) can be used to accommodate adjustable legs (not shown) for leveling the pipe jack. On the inside of the body are a pair of longitudinally extending channels 14, 14' which provide flanges on which a carriage 20 can reciprocate. The carriage carries an elongate sleeve 25 through which a pointed pipe 28 can be received. A hydraulic ram 30 moves the carriage 20 and drives the sleeve 25 against a gripping mechanism, generally designated 40. When the carriage 20 has been extended to its fullest, as shown in FIG. 4, the gripping mechanism is released, the carriage retracted to the position illustrated in FIG. 5, and the operation repeated to jack the pipe.

The tubular body 10 is approximately square in cross-section, advantageously formed from $\frac{1}{4}$ inch steel and having outside dimensions of 6 inches by 6 inches by 36 inches long. As best seen in FIG. 3, it has a lower wall 41 to which the legs are mounted, and substantially upright side walls 42 and 42' on which the channels 14 and 14', respectively, are mounted. At the top are inwardly projecting flanges 44 and 44' which overlie a portion of the carrier 20, and which are spaced apart to provide a elongate slot extending the full length of the tubular body. At the rear end of wall 44 is an outwardly extending shelf 46 on which a control valve 48 is mounted. The rear or left end of the tubular body is closed by two angle brackets 51 and 52 having their legs extending forwardly to provide a bracket on which the hydraulic cylinder 30 is mounted by way of a pin 53 and a clevis 54. As best seen in FIG. 4, wall 42 has a reduced height near the rear end of the tubular body to provide easy access to the pin 53 for mounting or dismounting the cylinder.

The carrier 20 is advantageously formed from $\frac{1}{8}$ inch steel and has an inverted U-shaped cross-section providing legs 62 and 62' which lie closely adjacent the upright sides 42 and 42' of the body 10. An upper wall 64 of the carrier extends across the elongate slot of the body. At the bottom of wall 64 is fixed a mounting bracket formed by two channels 65 and 66 having an opening for receiving a pin 67 which attaches to a clevis 68 at the end of a piston rod 69 of the hydraulic cylinder 30. The carrier is preferably of shorter length than the elongate body 10 and, for this purpose, advantageously has a length of about 32 inches.

The hydraulic cylinder 30 advantageously has a stroke about a quarter of the length of the carrier and, in the embodiment illustrated, has a stroke of 8 inches. Suitable hydraulic connections (not shown) lead from the valve 48 to the cylinder 30 so that hydraulic fluid can be selectively fed to either side of the piston (not shown) contained in the cylinder. For this purpose, the valve 48 is a two-position, four-way valve.

Sleeve 25 has an inner surface which is in the form of a right circular cylinder and, in the embodiment illustrated, has a 2 inch inner diameter. The length of the sleeve 25 is preferably several times its diameter and, in the embodiment illustrated, has a length of about 26 inches. The sleeve is welded to a plate 72 which is preferably removably mounted on the top wall 64 of the carrier by means of a plurality of bolts 74.

At the top of the body 10 is a super structure 76 in the form of an inverted U-shaped member the legs of which are welded to flanges 44 and 44'. The super

structure overlies the sleeve 25 and is so arranged that a post can bear against it and hold the entire pipe jack firmly against the floor.

Referring again to FIGS. 1 and 2, the gripper 40 is formed from a heavy steel plate bent into a shape which includes an L-shaped portion and a circular portion. The L-shaped portion is formed of legs 81 and 82. The circular portion includes a first arcuate member 83 and a second arcuate member 84 which is connected to the first arcuate member by a hinge 85. A hydraulic ram 86 is mounted on leg 81 and has an extensible portion 87 which, when extended, engages the outer surface of arcuate member 84 and grips the pipe or rod 28 between it and member 83. When the extensible portion 87 is retracted, it can be seen that arcuate member 84 can swing relative to member 83 thereby releasing the grip on the rod and allowing the gripper to be quickly and easily repositioned.

While a preferred embodiment of the invention has herein been illustrated and described, this has been done by way of illustration and not limitation, and the invention should not be limited except as required by the scope of the appended claims.

I claim:

1. A pipe jack comprising: a tubular body having a cross-section generally in the form of a square tube with upright sides, and front and rear ends; the tubular body being open at the front end and having an elongate slot in its top extending rearwardly a preselected distance from the front end; a carrier mounted in the tubular body between the sides and below the top thereof and having an inverted U-shaped cross-section the legs of which lie closely adjacent the upright sides of the tubular body; the tubular body having inwardly projecting flanges at its top which overlie a portion of the top of the carrier and define the elongate slot; the carrier being slidable between a retracted position and an extended position where it extends through the open front end of the tubular body; a sleeve for receiving a length of pipe; the sleeve having an inner surface in the shape of a right circular cylinder the axis of which is parallel to the slot; the sleeve having a length several times its inside diameter; means on the carrier and extending through the elongate slot of the tubular body for removably mounting the sleeve on the carrier; a cylinder disposed entirely within the tubular body and between the legs of the carrier, and having a piston and a piston rod; means for attaching the cylinder to the tubular body; a bracket depending from the underside of the carrier for attaching the piston rod to the carrier with the axis of the piston rod parallel to the axis of the sleeve; means for selectively feeding fluid under pressure to the cylinder to move the piston and piston rod and thereby move the carrier relative to the tubular body; gripping means for gripping the pipe adjacent the sleeve and including: first and second arcuate members substantially surrounding the pipe, means hingedly connecting said arcuate members, and fluid operated means for applying force to said arcuate members to clamp the pipe between them; and said arcuate members providing a surface facing the sleeve for engage-

ment thereby, whereby the pipe is jacked as the carrier is moved.

2. A pipe jack as set forth in claim 1 including laterally-extending legs secured at opposite sides of the tubular body and having openings for receiving anchoring apparatus; and a superstructure secured to the tubular body and immovable relative thereto; the superstructure having a portion extending over the sleeve and against which a hold down force may be applied.

3. In a rod and pipe pushing and pulling device including an elongate body, a carrier slidably mounted on the body, and a hydraulic cylinder for moving the carrier relative to the body; characterized in that the carrier and hydraulic cylinder are both disposed within the elongate body; the elongate body has a rear end, an open front end, and an elongate slot in the top thereof extending rearwardly a preselected distance from the front end; the elongate body has a cross-section generally in the form of a square tube having upright sides; the carrier has an inverted U-shaped cross-section the legs of which lie closely adjacent the upright sides of the tubular body; the tubular body having inwardly projecting flanges at its top which overlie a portion of the top of the carrier and which define the elongate slot; the carrier being slidable between a retracted position and an extended position where it extends through the open front end of the body; a sleeve disposed outwardly of the elongate slot and having an inner surface in the shape of a right circular cylinder; said sleeve having a length about 13 times its inside diameter; means operatively connecting the sleeve to the carrier for movement therewith and including a plate disposed in said elongate slot and secured to the sleeve, and fastening means removably mounting the plate on the carrier; a superstructure secured to the elongate body and extending over the sleeve and against which a hold down force may be applied; and an apparatus for clamping the rod and for engagement by the sleeve so that the rod is advanced as the sleeve is moved by the carrier.

4. In a rod and pipe pushing and pulling device including an elongate body, a carrier slidably mounted on the body, a hydraulic cylinder for moving the carrier relative to the body, and gripping means for gripping the rod and providing a surface for engagement by the carrier so that the rod is moved along with the carrier; characterized in that the gripping means includes an L-shaped member; a first arcuate member attached at the extremity of one leg of the L-shaped member and with its inner surface facing the other leg; a second arcuate member hinged to the first arcuate member and with its outer surface facing said other leg; and a hydraulic ram mounted on said other leg and operative, when extended, to engage the outer surface of the second arcuate member to grip the rod between the two arcuate members and, when retracted, permitting the second arcuate member to swing thereby releasing the grip on the rod.

5. A pipe jack as set forth in claim 2 wherein the length of the sleeve is about 13 times its inside diameter.
